UNITED STATES PATENT OFFICE.

EDWARD F. GEIGER, OF CHICAGO, ILLINOIS, ASSIGNOR TO INTERNATIONAL TIME RE-CORDING COMPANY OF NEW YORK, OF BINGHAMTON, NEW YORK, A CORPORATION OF NEW YORK.

WATCHMAN'S DELINQUENCY ALARM.

Application filed April 4, 1925. Serial No. 20,612.

The present invention relates to a delinquency signal system for watchmen's time recording systems.

At the present time there are numerous installations of watchmen's recording systems which include a plurality of remotely located watchmen's stations usually electrically connected to a recorder at a central office. The watchman making his rounds inserts his key 5 at each station and thereby effects a record in the central recorder which designates the time of making a record, the station number and other like data.

The present invention is directed to the provision of a simple signal device which will give a suitable alarm which may be visual or audible or both in the event that the watchman has delayed over a determined time interval in turning in a report from any of a 10 plurality of stations.

It has for its primary object the production of a system of the nature outlined which will be dependable in its operation and subject to very precise adjustment.

Further and other objects of the present invention will be pointed out hereinafter in the accompanying specification and claims and will be shown in the drawings which by way of illustration show one and a 15 preferred embodiment of the invention.

In the illustration, I have shown a general view of the indicating circuits in cooperative relation with the timing mechanism at a watchman's station.

These timing mechanisms are each enclosed within a recorder case 9 and are distributed along a route which the watchman is required to patrol. Each watchman is provided with a crank or key of special design 20 which gives him access to the recorder and shaft 10 for the purpose of recording his appearance and rotating the shaft. To shaft 10 is fastened cam 11 which strikes friction roller 12 on lever 13 every time the shaft is 25 rotated. Lever 13 is rotatably mounted at one end to a shaft 14 and carries at its other end a stud for supporting the lower end of rod 15. Movement of lever 13 is transmitted to lever 16 which is loosely mounted on shaft 30 17. This lever is continuously urged downward by spring 18, but its rapid descent is prevented by the engagement of spring

pressed pawl 19 carried thereon with ratchet wheel 20 fixed to gear 21 and loosely mounted on shaft 17. Gear 21 drives pinion 22 which 35 in turn operates gear 23 to actuate the escapement ratchet 24. Verge 25 is mounted on a spindle and is oscillated by pendulum 26 as is usual in clock mechanisms.

It is apparent from the foregoing that the 40 motive power for this timing mechanism is derived through spring 18 and that the spring is tensioned for continuous operation each time shaft 10 is rotated. The design of the timing mechanism bears a direct relation to 45 the frequency of operation of each watchman's recorder, and any time controlling mechanism can be used.

Normally, during the watchman's tour of 50 duty, a white light is apparent at the central station, but if he should fail to operate a particular recorder, indication thereof would be given in the nature of an audible signal or the 55 burning of a colored light. The circuit illustrated is closed with the white light burning 75 and the current is taken from main lines by feed wire 27 and thence flows through magnet 28, line 29, contact 30, line 31, and to the source of power through feed line 32. Another branch of current flows through arma- 80 ture 33, line 34, and illuminates light 35.

When contact 30 is broken, these two circuits are opened and current from feed line 27 flows through circuit 38 and causes bell 39 to ring and light 40 to glow. These signals 85 will continue to be apparent until the watchman makes his appearance at the proper station and operates the recorder.

Contact 30 is placed so that it will be broken when lever 16 has descended below its allowed maximum which will occur a short time 90 after the watchman should have reported.

It is also apparent that any interference such as severing the lines connecting the various stations with the central station 95 would be immediately manifested by the bell and colored light or any other means for indicating the break in the main circuit.

All of contacts 30 may be placed in series along line 29-31 so that the opening of any 100 one will give the desired signal, but if the number of stations are few, or the interval between reports long, or the routes of great importance, it would probably be found to be

more desirable to have individual signaling circuits for each station.

What I claim is:

1. In a system of the class described, the 5 combination of circuits which are continually excited under normal conditions, means in one of said circuits for indicating their condition, time controlled means in the other of said circuits for opening both of said circuits, 10 means controlled by one of said circuits and said last named means for closing a third circuit, and indicating means in said third circuit to indicate the condition thereof.

2. In a system of the class described, the 15 combination of circuits which are continually excited under normal conditions, a circuit subject to be closed when said first named circuits are opened, time controlled means for opening said first named circuits, and indicating means affected by the excitation of 20 said circuits to indicate which of said circuits are closed.

3. In a system of the class described, the 25 combination of indicating means and a circuit for energizing the same, another circuit to maintain said first named circuit closed, time controlled means for opening said latter circuit, and a third circuit automatically closed at the operation of said time controlled means 30 for energizing a signal.

4. In a system of the class described, the 35 combination of a plurality of signaling means, circuits for energizing the same, time controlled means for automatically selectively determining which of said signaling means shall be energized before and after a predetermined time, and a watchman's recorder connected with said time controlled means for

preventing the time controlled means from affecting the circuits at the predetermined 40 time.

5. In a watchman's signaling system, a normally operative signal, time controlled mechanism for rendering said signal inoperative at the expiration of a predetermined 45 period of time, a second signal, means for automatically rendering said second signal operative upon said first signal being rendered inoperative and manually controlled means for suspending the operation of said 50 time controlled mechanism until the expiration of a further period of time.

6. In a watchman's signaling system, a normally operative signal, time controlled mechanism for rendering said signal inoperative at the expiration of a predetermined period of time, a second signal, means for automatically rendering said second signal operative upon said first signal being rendered inoperative and key controlled means 60 for suspending the operation of said time controlled mechanism until the expiration of a further period of time.

7. In a watchman's signaling system, a normally operative signal, a second signal 65 normally inoperative, a relay for controlling the operation of said signals, time controlled mechanism for operating said relay at the expiration of a predetermined period of time and key controlled means for suspending the 70 operation of said time controlled mechanism until the expiration of a further period of time.

In testimony whereof I hereto affix my signature.

EDWARD F. GEIGER.
